UNITED STATES PATENT OFFICE.

JOHN H. LONDICK, OF ALMA, MICHIGAN.

VALVE-GEAR AND IGNITION MECHANISM.

976,478.

Specification of Letters Patent. Patented Nov. 22, 1910.

Application filed January 2, 1909. Serial No. 470,498.

To all whom it may concern:

Be it known that I, JOHN H. LONDICK, a citizen of the United States, residing at Alma, in the county of Gratiot, State of Michigan, have invented certain new and useful Improvements in Valve-Gear and Ignition Mechanism; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to valve gear and ignition mechanism for internal combustion engines, and consists in the construction and arrangement of parts hereinafter more fully set forth and pointed out particularly in the claims.

The object of the invention is to produce a comparatively simple and efficient valve mechanism, and to associate with and operate in conjunction with the valve mechanism an igniter whereby the speed of the engine may be controlled through the operation of a centrifugal governor.

A further object of the invention is to provide efficient mechanical means for carrying into effect the operations above set forth.

The above objects are attained by the mechanism illustrated in the accompanying drawings, in which:—

Figure 1 is an elevation of an engine of the internal combustion type, showing the operative parts in connection therewith which embody my invention. Fig. 2 is an enlarged fragmentary view partly in section of the valve controlling and spark producing mechanism. Fig. 3 is a similar view showing the position of said parts at a different period in the cycle of operation. Fig. 4 is a plan view of the block in which the electrodes are mounted, showing the ends of said electrodes and a portion of the igniter rod. Fig. 5 is an enlarged fragmentary view in section through a portion of the wall of the explosion chamber, showing the block carrying the electrodes seated therein, and some of the parts for actuating the movable electrode. Fig. 6 is a sectional view through the mechanism showing the position of parts during the exhaust stroke. Fig. 7 is a similar view showing the position of parts during the compression period. Fig. 8 is an enlarged sectional view through a bracket which supports the valve rod, showing the electro-magnet for actuating the latch to release said rod. Fig. 9 is a plan view of the parts shown in Fig. 8.

Referring to the characters of reference, 1 designates a cylinder which may be of the type commonly employed in internal combustion engines. Within the cylinder is the ordinary piston, not shown, to which is attached a connecting rod 2 which is in turn journaled on the crank 3 of the crank shaft 4 which carries the usual fly wheel 5. Upon the outer end of the shaft 4 is a cam ring or collar 6 having a raised cam face 7. The crank shaft is journaled in supports 8 rising from the frame 9 upon which the cylinder 1 is mounted. Supported at one end to slide longitudinally in a bracket 10 which is carried on the frame, is a valve rod 11. The other end of said valve rod is supported to slide longitudinally in a bracket 12 carried on the cylinder of the engine. The end of the valve rod adjacent the crank shaft is provided with an antifriction roller 13 which is adapted to roll upon the surface of the cam 7, whereby longitudinal movement is imparted to said rod in one direction. To return said rod after being acted upon by said cam, a coiled spring 14 is employed which is confined between a collar 15 fixed on the valve rod and the end of the bracket 12, the arrangement being such that as the valve rod is moved forward by the action of the cam, said spring is compressed, the tension of which returns said rod after the high point of the cam has passed from engagement with the roller 13. By this arrangement a reciprocatory movement of the valve rod is provided for. Depending from the collar 15 is an arm 16 which is connected to the piston rod of a pump 17 through the operation of which gasoline is supplied to the carburetor of the engine, as will be well understood. Carried by the forward end of the valve rod and rigidly secured thereto are the parallel standards 18 which are spaced from each other and between which is pivoted at 19 the oscillatory lever 20. The lower end of the lever 20 is provided with a horizontally projecting portion 21 in the under side of which is formed a notch 22. Pivoted mounted at 23 between the lower ends of the standards is a detent 24 to the rear face of which is

secured a curved spring 25 which extends vertically and whose upper end engages a pin 26. The lower end of the spring 15 extends downwardly below the standards 18 and is provided with a projecting point 27. Pivoted to the under side of the bracket 12 is an arm 28, the forward end of which is notched and the inner end of which carries an adjusting screw 29.

- 10 Within the case 30 inclosing the combustion chamber 31 is an intake valve 32, the stem 33 of which passes through the wall of the intake pipe 34 and carries a seating spring 35. Also within the combustion chamber 15 is seated the exhaust valve 36 which controls the passage to the exhaust port 37. The stem 38 of the exhaust valve passes through the case 30 and its outer end stands directly in alinement with the end portion 21 20 of the oscillatory lever 20. Mounted upon the outer end of the stem of the exhaust valve is a seating spring 39.

Pivoted at one end to the upper end of the oscillatory lever 20 is the igniter rod 25 40 the opposite end of which is carried to reciprocate in a support 41. Rotatable in a block 42 which extends into the combustion chamber is a shaft 43 carrying the movable electrode 44. The upper end of the shaft 43 extends through said block and has attached thereto the flat curved spring 45. Embracing said shaft is a coiled spring 46, one end of which is attached thereto and the other end to the bearing through which 35 the shaft passes. The fixed electrode 47 passes through the block 42 and is insulated therefrom, the inner end of said electrode being adapted to be engaged by the free end of the electrode 44 to form the, so called, 40 make and break spark, as will be well understood. Fixed to the igniter rod 40 is a catch 48, which, as said rod moves in one direction is adapted to engage the flat spring 45 and swing the shaft 43 against the action of the 45 spring 46 to carry the movable electrode into contact with the fixed electrode, at the same time placing sufficient tension upon the spring 46 as to cause a sudden separation of said electrodes when said catch passes from engagement with the spring 45, thereby 50 producing a spark between the electrodes, as is common in the art.

Mounted in the bracket 12, as shown in Fig. 8, is an electro-magnet 49 having a pole piece 50 extending through said bracket. Pivoted at 51 to the exterior of the bracket 12 is a gravity latch 52 one end of which stands adjacent the pole piece of said magnet, the other end of said latch projecting 60 inwardly at right angles through an opening in said bracket and being beveled, as shown at 53, to engage a notch 54 in the valve rod when said rod by a movement thereof causes said notch to register with said latch.

Fixed to a portion of the engine frame is a disk 55 of insulating material having seated therein a contact 56. Secured at 57 to a spoke of the fly-wheel is a spring arm 58 carrying at its free end a weighted contact 59 adapted by the rotation of the fly-wheel to wipe across the contact 56 once during each rotation of said wheel while the engine is running at normal or below normal speed. The contact 56 in the disk 55 is in 75 circuit with a battery 60 (see Fig. 1) through the circuit wire 61. The other side of the circuit is completed through the wire 62, the primary winding 63 of the induction coil, the wire 64 which leads to the binding screw 65 on the engine frame, thence through the frame of the engine to the wiping contact 59 on the free end of the spring arm 58, whereby as often as the contacts 56 and 59 are brought together, the circuit including the source of electric energy, will be closed through the primary winding of the induction coil. Leading from the wire 62 is a branch wire 66 which connects with one terminal of the winding of the electro-magnet, the other terminal of said winding being connected to the wire 67 which leads to the binding post 65, thereby completing a circuit through the coil of the electro-magnet whenever the contacts 56 and 59 are 95 brought together, and energizing said magnet to actuate the latch upon its pivot and withdraw the beveled end thereof from contact with the notch in the valve rod, for purposes hereinafter explained.

The secondary winding 68 of the induction coil is connected through the wire 69 with the fixed electrode 47 and through the wire 70 with the movable electrode 44 by grounding said wire on the case 30, whereby 105 upon the closing of the primary circuit, a secondary current will be generated in the lines leading to said electrodes.

In the operation of the engine, the rotation of the shaft 4 will cause the cam 7 to engage the autifriction roller 13 at the rear end of the valve rod to carry said rod forward to the limit of its movement, at which time the beveled end 53 of the latch 52 will engage in the notch 54 of said rod and lock 115 it at the limit of its forward movement, a position of parts shown in Fig. 6, in which position the parts remain while the engine is running above normal speed, and in which position the exhaust valve is opened and the 120 ignition mechanism and valve rod are inactive, the spring 14 which returns the valve rod to its normal position remaining under compression. When the speed of the engine falls to or below normal, the spring arm 58 carrying the wiping contact 59 will permit said contact, as the fly wheel revolves at a slower speed, to wipe over the contact 56 on the disk 55 and close the circuit through the electro-magnet 49, thereby energizing said 130

magnet and actuating the latch 52 to release the valve rod 11, allowing the spring 14 to return said rod to its normal position into contact with the low point of the cam ring 5. At the time the valve rod has nearly reached the limit of its rearward movement, the oscillatory lever 20 will come into contact with the stop screw 72 which is mounted in the bracket 12 and which serves as a stop 10 for said lever, causing it to swing slightly upon its pivot 19 and release the detent from the notch at the lower end thereof. The free end of said detent when so released is caused to swing downwardly below the 15 plane of said notch through the action of the curved flat spring 25 attached thereto as said spring is allowed to return to its curved form after the disengagement of the detent from said lever. The position of parts is 20 such that the release and return of the valve rod always takes place at the time the piston has reached the limit of its outward stroke (in engines of the four cycle type) so that the parts are in position upon the closing of 25 the exhaust valve to commence the intake stroke, which stroke is completed while the low point of the cam ring is in engagement with the roller in the end of the valve rod. During the inspiration of the engine, or the 30 period of intake, the intake valve will be unseated against the action of the spring 35 to permit an explosive charge to enter the cylinder, said charge being drawn through a carburetor, not shown, connected with the 35 intake pipe 34, past the intake valve and through the port 71 leading to the cylinder. At the completion of the intake stroke, the compression stroke begins which is illustrated in Fig. 7, in which view the parts are 40 shown in the position they occupy shortly after the commencement of said stroke, the valve rod having been forced forward by the cam but the exhaust valve remaining closed owing to the fact that the detent 24 is not in engagement with the oscillatory 45 lever 20, permitting the lower end of said lever to recede when it encounters the stem of said valve. At the completion of the compression stroke, a position of the parts 50 illustrated in Fig. 3, the wiping contact 59 will encounter the contact 56 at the moment the cam passes from engagement with the antifriction roller in the end of the valve rod, thereby energizing the electro-magnet 55 49 to actuate the latch 52 and release the valve rod to permit its return by the action of the spring 14. It will be noted on referring to Fig. 7 that as the valve rod is advanced on the compression stroke, the upper 60 end of the oscillatory lever 20 is thrown forward and the igniter rod 40 is moved horizontally by the combined movement of said lever and the valve rod to carry the catch 48 thereon past the free end of the spring 45 65 on the shaft of the movable electrode 44.

Upon the return of the valve rod when released by the latch 52 at the completion of the compression stroke and while contacts 56 and 59 are still in engagement, the stop screw 72 will encounter the oscillatory lever 70 20 below its point of pivot, thereby moving said lever upon said pivot and imparting an accelerated rearward movement to the upper end thereof, which movement draws upon the igniter rod to cause the catch 48 to slip 75 from the spring 49 and allow the movable electrode to quickly move from contact with the fixed electrode, causing a spark and exploding the compressed charge in the cylinder. At about the time the oscillatory lever 80 encounters the stop screw 72 upon the return of the valve rod, the lower free end of the spring 25 will engage the forward end of the arm 28 so that the last portion of the rearward movement of the valve rod will 85 place a tension upon said spring which will cause the free end of the detent 24 to bear upwardly against the lower end of the oscillatory lever and enter the notch 22 in said lever at the moment the valve rod shall have 90 reached the limit of its rearward travel. The position occupied by the parts as above described prior to the instant of explosion is shown in Fig. 3. At the completion of the explosion stroke, the parts enter upon the exhaust stroke, as shown in Fig. 6. During the period of exhaust, the position of the parts is the same as when the engine is running above normal speed. At the completion of the exhaust stroke should the speed of the 100 engine be below normal which is the position illustrated in Fig. 2, the wiping contact 59 will engage the contact 56 and energize the electro-magnet to release the valve rod and place the parts in position for the inception of the intake stroke. It will of course 105 be understood that when the engine is running above normal, centrifugal force will throw the weighted contact 59 outwardly against the action of the spring arm 58 and prevent its engagement with the contact 56 until the speed of the engine is reduced.

It will now be apparent that by means of the mechanism herein shown and described, provision is made for effectively controlling 115 the valve and ignition mechanism in accordance with the speed of the engine and for alternately actuating the exhaust valve when running at normal speed.

Having thus fully set forth my invention, 120 what I claim as new and desire to secure by Letters Patent, is:—

1. In a valve gear and ignition mechanism, the combination with an engine shaft, of a cam thereon, a reciprocatory valve rod 125 actuated by said cam, an exhaust valve and an igniter actuated by said rod, a latch for locking said rod against movement, an electro-magnet for releasing said rod, an electric circuit including said magnet, and means 130

for closing said circuit at a predetermined point in the rotation of said shaft.

2. The combination with an engine shaft, a valve rod actuated thereby, a pivoted lever 5 on the valve rod, a valve movable independently of the valve rod and adapted to be operated by said lever through the movement of said rod, an igniter comprising a movable electrode, said electrode being actuated by a movement of said valve rod, means 10 for locking said valve rod against movement, and means for releasing said locking means actuated by the rotation of the engine shaft.

15 3. The combination with an engine shaft, of a valve rod actuated thereby, a valve and an igniter actuated by a movement of said rod, a latch for locking the valve rod, an electro-magnet for releasing said latch, 20 an electric circuit including said magnet and said igniter, and means operated by a rotation of the shaft for closing said circuit.

4. The combination with an engine shaft, of a valve rod actuated thereby, a valve, 25 independent of the valve rod, means carried by the valve rod for causing a movement of said valve concurrent with the movement of the rod, said means at intervals permitting a movement of the valve rod without actuating said valve, means for locking the valve rod against movement, and means actuated by the rotation of said shaft for releasing said locking means.

35 5. In a valve gear and ignition mechanism, the combination with an engine shaft, of a valve rod actuated thereby, a valve and an igniter actuated by a movement of said valve rod, a latch for locking the valve rod against movement, an electro-magnet for 40 releasing said latch, an electric circuit including said magnet and said igniter, a fixed contact with which one terminal of said circuit is connected, a wiping contact with which the other terminal of said circuit is 45 connected, said wiping contact being carried across the fixed contact as the engine shaft rotates.

6. In a valve gear and ignition mechanism, the combination with an engine shaft, 50 of a valve rod actuated in one direction thereby, means for actuating said rod in the opposite direction, a valve and an igniter connected with said valve rod to be operated by the travel thereof, a latch for locking the valve rod against movement, an electric circuit including said igniter, and means actuated in accordance with the speed of the engine for intermittently closing said circuit and releasing said latch.

55 60 7. The combination with an engine shaft, of a valve rod actuated in one direction only thereby, a pivoted lever carried by said rod, a valve independent of the valve rod operated by said lever through a movement of 65 said rod, a latch for locking the valve rod

against movement, and means operated in accordance with the speed of the engine for releasing said latch.

8. The combination with an engine shaft, 70 of a valve rod adapted to be actuated thereby, a valve actuated by a movement of said rod, a latch for locking the valve rod against movement, an electro-magnet for releasing said latch, an electric circuit including said magnet, and a circuit closer movable with 75 the engine shaft and actuated in accordance with the speed thereof to intermittently close said circuit.

9. The combination with an engine shaft, 80 of a valve rod actuated thereby, a valve, detached from said rod, a pivoted lever carried by the valve rod adapted to move said valve when locked, means for locking said lever to cause it to actuate said valve by a movement of said rod, and means for releasing 85 said lever to enable a movement of the valve rod without actuating said valve.

10. The combination with an engine shaft, 90 of a valve rod actuated thereby, a valve, a pivoted lever carried by the valve rod, means for locking said lever to cause it to actuate said valve by a movement of said rod, means for releasing said lever to enable a movement of the valve rod without actuating said valve, means for locking the valve rod 95 against movement, and means actuated in accordance with the speed of the engine for releasing said locking means to permit a movement of the valve rod.

11. The combination with an engine shaft, 100 of a valve rod actuated thereby to travel in one direction, means for moving said rod in the opposite direction, a pivoted lever carried by the valve rod, a valve, means for locking said lever to cause it to actuate said 105 valve by a movement of said valve rod, means actuated by the travel of the valve rod for releasing said lever to enable a movement of the valve rod without actuating said valve, a latch for locking the valve rod 110 against movement, and means actuated in accordance with the speed of the engine for releasing said latch.

12. In a valve gear and ignition mechanism, the combination with an engine shaft, 115 a reciprocatory valve rod actuated thereby, a pivoted lever carried by the valve rod, a valve, means for locking said lever to cause an actuation of the valve by a movement of said valve rod, an igniter connected with 120 said lever, means for releasing said lever to enable a movement of the valve rod without actuating said valve, and means for moving said lever upon its fulcrum independently of the movement imparted thereto by the 125 travel of the valve rod to actuate the igniter.

13. The combination with an engine shaft, 130 of a reciprocatory valve rod actuated thereby, a pivoted lever carried by the valve rod, an igniter having a movable electrode, means

connecting said movable electrode with said lever, means for locking said lever against movement on its pivot, a valve actuated by said lever when locked through a movement 5 of the valve rod, and means for releasing said lever to permit a movement of the valve rod without actuating said valve.

14. The combination with an engine shaft, of a reciprocating valve rod actuated there- 10 by, a pivoted lever carried by the valve rod, an igniter having a movable electrode, means connecting said movable electrode with said lever, means for locking said lever against movement on its pivot, a valve actuated by 15 said lever when locked through a movement of the valve rod, means for releasing said lever to permit a movement of the valve rod without actuating said valve, means for locking the valve rod against movement 20 when in its forward position, and means ac-

tuated in accordance with the speed of the engine for releasing said locking means to permit a movement of said valve rod.

15. The combination with an engine shaft, a valve rod actuated thereby to move in one 25 direction, means for moving the valve rod in the opposite direction, a pivoted lever carried by the valve rod, a detent for locking said lever against movement upon its pivot in one direction, a valve positioned to be 30 actuated by said lever when locked, and means for disengaging said detent from said lever at the limit of the rearward movement of the valve rod.

In testimony whereof, I sign this specifica- 35 tion in the presence of two witnesses.

JOHN H. LONDICK.
